(57) **CLAIM**

I claim the ornamental design for a bottle, as shown and described.

DESCRIPTION

FIG. 1 is a perspective view of a bottle in accordance with a first embodiment of my new design.

FIG. 2 is a front elevational view of the bottle in FIG. 1, the side elevational views and the rear elevational view of the bottle in FIG. 1 being identical to FIG. 2.

FIG. 3 is a top plan view of the bottle in FIGS. 1 and 2, the bottom forming no part of the claimed design.

FIG. 4 is a perspective view of a bottle in accordance with a second embodiment of my new design.

FIG. 5 is a front elevational view of the bottle in FIG. 4, the side elevational views and the rear elevational view of the bottle in FIG. 4 being identical to FIG. 5; and,

FIG. 6 is a top plan view of the bottle in FIGS. 4 and 5, the bottom forming no part of the claimed design.
